METHOD OF PRODUCING LOW BOILING HYDROCARBONS

William O. Keeling, Independence, Mo.

Application June 7, 1929, Serial No. 369,175

2 Claims. (Cl. 196—66)

This invention relates to a process of and apparatus for converting high boiling hydrocarbons into low boiling hydrocarbons, and has for its object to provide, in one continuous operation and in a manner as hereinafter set forth for the cracking of the heavy ends of the cracking stock in the vapor phase by the introduction of fresh hot gases or vapors at one or more fixed independent points and further for distilling off the lighter ends of the cracking stock resulting in an unusually satisfactory and inexpensive product, the properties of which are substantially gravity A. P. I. 45° to 55°, aniline cloud point under 30° C., unsaturates (by H_2SO_4) between 20—50%, A. S. T. M. boiling point ranges as for commercial gasolines, H. U. C. R. 5.5 to 7.0 and iodine No. 150 to 250.

This application is a continuation in part of my copending application, Serial No. 223,054, filed September 30, 1927.

A further object of the invention resides in the maintaining of the cracking temperature by the introduction of fresh hot gases or vapors at fixed independent points without the supplying of air for combustion purposes to the cracking chamber or chambers whereby the cracking operation, in accordance with this invention is carried out at a materially less expense with respect to the processes now employed for the same purposes.

A further object of the invention is to provide, in a manner as hereinafter set forth, whereby the cracking is had with the avoiding of excessive deposition of carbon and with a flexible control of cracking temperature.

A further object of the invention is to provide, in a manner as hereinafter set forth, the combination of cracking and distillation in one unit.

A further object of the invention is to provide, in a manner as hereinafter set forth, whereby a conservation of heat is had due to direct contact between the heating agents and oil to be cracked and the oil to be distilled.

A further object of the invention is to provide, in a manner as hereinafter set forth, for the introduction of fresh hot gases or vapors, of any kind at a plurality of fixed, independent points and then expanding the mixture after the introduction of each fresh charge of hot gas or vapor.

A further object of the invention is to provide, in a manner as hereinafter set forth, for regulating the temperature of the fresh hot gas or vapor at each point of introduction in order that the composition of the cracked products may be varied as desired.

A further object of the invention is to provide, in a manner as hereinafter set forth, whereby after the last expansion of the mixture, the heat in the cracked oil vapors and heating gases or vapors is utilized to distill off the lighter end of the charging stock.

A further object of the invention is to provide, in a manner as hereinafter set forth, whereby the vapors and gases pass through fractionating columns where the various fractions can be separated.

A further object of the invention is to provide, in a manner as hereinafter set forth, for recirculating the gases or vapors, using part or all of them to vaporize cracking stock or to crack a vaporized charging stock.

A further object of the invention is to provide for compressing oil vapors and fixed gases, if desired, before finally condensing the former.

With the foregoing and other objects in view the invention consists of the new, novel, improved, expeditious means in a manner as hereinafter referred to for converting high boiling hydrocarbons into low boiling hydrocarbons by cracking, but it is to be understood that changes in the details of the process and apparatus can be had which will fall within the scope of the claims hereunto appended.

As illustrating one form of an apparatus capable of carrying out the process, in accordance with this invention, for converting high boiling hydrocarbons into low boiling hydrocarbons, reference is had to the accompanying drawing which illustrates such apparatus diagrammatically.

The manner of converting high boiling hydrocarbons into low boiling hydrocarbons and for distilling off the lighter ends of the cracking stock, the converting and distilling being carried on continuously and in one unit is as follows:

Cold charging stock to the unit is split into two streams, one of which goes through the final heat exchanger or partial condenser to extract heat from the fractionated gasoline and fixed gases and part goes through reflux condensers in the top of each column or tower, either in series or in parallel. The apparatus or unit as illustrated shows it going through each column in series. The stream from the partial condenser next passes through a heat exchanger, not shown, through which the hot residuum from the vaporizing column is pumped and cools the residuum down so that it can be pumped to storage.

The two streams of charging stock next come together again and empty on to one of the decks or trays in the stripping column, said tray being

determined by the nature of the charging stock. The stock travels down the column counter-current to hot ascending gases or vapors or mixture of both. The lighter ends of the charging stock 5 are distilled off over into the first fractionating column or tower. The hot bottoms are pumped to the vaporizer column.

The oil vapors from the cracking zone together with those from the stripping column pass into 10 the bottom of the first fractionating column where the heaviest ends of the oil are fractionated out and returns to the bottom of the column from where it is picked up by pump and pumped to the vaporizer column. It can be heated to a 15 temperature above its vaporization temperature enroute if desired. The vapors and gases pass to the second fractionating column where all the remaining hydrocarbons of boiling point greater than those contained in gasoline are fractionated 20 out and refluxed back to the vaporizer column. This refluxed oil can be drawn off from the bottom of the column and sold as furnace distillate or can be mixed with the refluxed oil in the first column, and pumped to the vaporizing column 25 25 or first mixing chamber as cracking stock.

The remaining vapors and the fixed gases leave the top of the second fractionating column and pass through the partial condenser where they give up part of the heat they contain to the cold 30 incoming charging stock or are compressed before going to final condenser. Any condensed gasoline is trapped off from the partial condenser to the separator. From the partial condenser the remaining vapors and gas pass through a water 35 cooled condenser where the rest of the condensable vapors are condensed. The fixed gases and condensed gasoline next go to the separator where the fixed gases and gasoline are separated. The gasoline is drawn off and pumped to storage. 40 The fixed gases containing a small amount of uncondensed gasoline vapors are drawn from the separator, compressed and sent through an absorption unit to remove the uncondensed gasoline. If gases are of sufficient pressure before 45 going to the final cooler the compression step is unnecessary. After this stripping, the fixed gases pass through a heater and thence through a manifold to the mixing chambers.

If the unit is operating on crude oil or residues, 50 the bottoms from the stripping column may be introduced into the vaporizing column. The bottoms from the first and second fractionating columns may be introduced into the first mixing chamber and there vaporized or may be also 55 introduced into the vaporizing column and there vaporized.

If the unit is operating on gas oil, the bottoms from the stripping column may be introduced into the vaporizing column and the bottoms from 60 fractionating columns 1 and 2 introduced either into the mixing chamber or into the vaporizer column for vaporization.

A portion of the bottoms from the vaporizing column can be recirculated over the column to 65 insure the greatest possible amount of volatile materials has been distilled off and the remainder can then be drawn off through the reboilers of the fractionating columns to help heat the refluxed oil from these towers.

70 The oil vapors and fixed gases passing from the top of the vaporizer column are mixed with fresh hot gases or vapors in the second mixing chamber and after thorough mixing to insure complete heat exchange, are expanded in the 75 first reaction chamber where such cracking occurs

as the temperature permits. On leaving the top of this reaction chamber, the mixture is again mixed with another fresh charge of hot gas or vapors and after thorough mixing for heat exchange is expanded into the second reaction 5 chamber where such cracking takes place as the temperature permits. This can be repeated as many times as desired.

The mixture of hot gases and vapors leaves the last reaction chamber and enters the bottom of 10 the stripping column. As it ascends this column it heats the charging stock and distills off the light ends. The term hot gases is to mean hot gases or hot vapors.

Referring to the drawing the apparatus as illustrated includes a stripping column 1 provided with spaced, superposed trays 2 and a reflux condenser 3 therein at the top thereof. A primary and a secondary fractionating column 4, 5 respectively, having therein at the tops thereof reflux condensers 6, 7 respectively. Each fractionating column has arranged therein spaced, superposed trays 8. The apparatus further includes primary and secondary reaction chambers 9, 10 respectively, a vaporizing column 11 provided with spaced, superposed trays 12, an absorption tower 13, a separator 14, a heat exchanger 15, a water cooled condensing coil 16, a heater 17, a pair of reboilers 18, 19 and a series 25 of mixing zones 20, 21, and 22.

The condenser 3 discharges into the top of column 1. The condenser 6 is closed to column 4 and opens into condenser 3 by a pipe branch 23 between columns 1 and 4. The condenser 7 is closed to column 5 and opens into condenser 6 by a pipe branch 24 between columns 4 and 5.

The apparatus further includes an incoming stock charging line 25 provided with a pair of branches 26, 27, the former extending through the heat exchanger 15 and opening into the discharge 28 of condenser 3. The branch 27 opens into the condenser 7. Leading from the bottom of the heat exchanger 15 and opening into the top of column 5 is a carrying off pipe 29 for the resultant product with the hot gases and vapors. Leading from the heat exchanger 15 to the separator 14 is a valve controlled pipe 30 for discharge of the heavier products.

Leading from the top of the heat exchanger 15 to the coil 16 is a valve controlled carrying off pipe 31 and communicating with the pipe 31 and coil 16 is a by-pass 32 having interposed therein a pump 33. Leading from the bottom of coil 16 and opening into the top of separator 14 is a discharge pipe 34. The separator 14 is closed. A valve controlled gasoline draw off pipe 35 leads from the bottom of separator 14.

The apparatus further includes a valve controlled carrying off pipe 36 leading from separator 14 to a pump 37 which opens into the bottom of tower 13. The pipe 36, in proximity to and above the controlling valve 38 thereof has extended therefrom a valve controlled branch 39 which opens into tower 13. Extending from the tower 13 to mixing chamber 20 and also through heater 17 is a hot gas or vapor supply pipe 40 having valve controlled branches 41, 42, the former opening into mixing chamber 21 and the latter into mixing chamber 22.

Leading from the top of column 11, communicating with mixing chamber 21 and opening into the bottom of reaction chamber 9 is a conducting pipe 43. Leading from the top of reaction chamber 9 is an outlet pipe 44 which opens into mixing chamber 22 and extending from the 75

- latter to the bottom of reaction chamber 10 is a conducting pipe 45. Extending from the top of reaction chamber 10 to the bottom of stripping column 1 is a conducting pipe 46. Leading from the top of column 1 to the bottom of primary fractionating column 4 is a conducting pipe 47 and leading from the top of column 4 to the bottom of secondary fractionating column 5 is a conducting pipe 48.
- 10 The reboilers 18, 19 are arranged below columns 4, 5 respectively, and discharge pipes 49, 50 respectively lead from columns 4, 5 respectively, and opening into reboilers 18, 19 respectively. Reboiler 18 is provided with a valved discharge pipe 51 which opens into branch 52 of a heated stock supply line and the latter further includes branches 53, 54, 55 and 56 and a pump 56'. The branch 52 leads from reboiler 19 to pump 56'. Branch 52 has a controlling valve 52' in proximity to reboiler 19. Pipe 51 opens into branch 52 below reboiler 18. Branch 53 leads from pump 56' to branch 54 and the latter opens into branch 55. Branch 56 leads from the bottom of column 1 to the lower end of branch 55 and the latter is adapted to communicate with the mixing chamber 20. Communication between branch 55 and chamber 20 is controlled by a valve controlled branch 57. Leading from branch 55 to column 11 is a series of superposed valve controlled inlet branches 58, 59, 60, 61 and 62 having associated therewith shut-off valves 63, 64, 65, 66 and 67 arranged in branch 55 above the points of communication between said inlet branches and branch 55. Below inlet branch 62, branch 55 is provided with a controlling valve 68. The hot gas or vapor supply line 40 has a controlling valve 69 in proximity to mixing chamber 20 and the controlling valves for the branches 41, 42 of line 40 are indicated at 70, 71 respectively.
- Leading from the bottom of column 11 is a valve controlled fuel line 72 which extends to storage not shown. The line 7 communicates with a pump 73 from which leads a vertically disposed branch 74 opening into column 11. The line 72 passes through the reboilers 18, 19. Leading from reboiler 19 is a valve controlled conducting line 75 which extends to storage not shown. Leading from the bottom of tower 13 is a valve controlled conducting line 76 extending to a fat oil still not shown.
- 50 With the cracking and fractionating part of the system working at low pressures, the combined gases and vapors from fractionating tower are drawn into pump 33 and compressed to desired pressure before they are discharged into condenser. This makes possible the use of a smaller condenser surface and because of the increased pressure, reduces the amount of gasoline vapors carried through the condenser by the fixed gases. If the system pressure is sufficiently great this pump can be bypassed, the vapors and gas from fractionating column discharging directly into condenser through bypass 32.
- The pump 73 is used to pump part of the bottoms from the vaporizer column up over the top 65 of the column to insure thorough stripping of all charging stock from the bottoms.
- The branch line 74 carries the oil from the discharge outlet of pump 73 and discharges the oil onto the top decks of the vaporizer column.
- 70 The tower 13 is an absorption tower where uncondensed gasoline vapors from the condenser and separator, carried along with the uncondensed gases, are stripped from these gases by means of absorption oil. This tower serves the same purpose as does an absorption tower in a

gasoline recovery plant extracting gasoline from natural gas.

The pump 37 is used to compress gases and vapors before their admission to the absorption tower if a pressure greater than that in condenser 5 or separator is desired. When the pressure in the condenser and separator is sufficiently great the pump 37 can be bypassed and the gases and vapors are admitted to the absorption tower through the bypass line 39.

10 The pipe 38 is used to draw off any gasoline condensate from the heat exchanger to the separator.

The reboilers 18 and 19 are sumps at the bottoms of the fractionating columns into which the reflux oil from each column gravitates. These reboilers are heated by closed coils through which hot residuum from the vaporizer column passes so that all light ends in the reflux are re-vaporized and again ascend the columns.

15 Valves 63, 64, 65, 66, 67 are manifold valves so arranged that the oil from reboilers 18 and 19 and bottom of stripping column can be introduced onto any plate of the vaporizer column desired.

20 The heat exchanger referred to is of conventional construction. Wherever exchangers are employed it should be understood one or more may be used and that all are of conventional design.

An example of working conditions and kinds and proportions of material is as follows:—

25 The charging stock is a topped residuum from a Mid-Continent crude. The gas used is a 50—50 mixture of methane and hydrogen. The residuum is charged into the stripping column 1 at substantially atmospheric temperature. The residuum is heated to approximately 650 degrees Fhr. by contact with the hot gases and cracked vapors from the last reaction chamber. At this temperature approximately 50% of it is vaporized, (the partial pressure effect of the gases enabling maximum vaporization at this low temperature.) The hot residuum is picked up by pump from the bottom of the stripping column and pumped through mixing chamber 20 or onto the lower trays in the vaporizer column 11. Condensed gas 35 oil is picked up by pump from the bottoms of fractionating columns 4 and 5 after passing through reboilers 18 and 19 where it is raised to approximately 500 degrees Fhr., and is discharged either into the mixing chamber 20 or into the upper decks of the vaporizing column.

40 Hot gas at about 1100-1200 degrees Fhr. is introduced into the bottom of the column through mixing chamber 20, and passes up through the column heating up the oil and vaporizing the gas 45 oil fractions. The temperature of the fuel oil drawn off from the bottom of column averages 650 degrees-700 degrees Fhr. and that of the oil on the top trays 500-650 degrees Fhr. The combined oil vapors and gases leave the vaporizing 50 column and pass through mixing chamber 21 where they are contacted with hot gas at about 1300 degrees Fhr. so that the temperature of the mixture is about 960 degrees Fhr. The proportion of gas to oil at this point is about 60 cu. 55 ft./gas to every gallon of oil vaporized in 11. The mixture is discharged into the first reaction chamber 9. Due to the heat absorption incident to the cracking reaction the temperature of the mixture leaving chamber 9 is about 935 degrees 60 Fhr. The mixture then passes through the mixing chamber 22 where it is mixed with hot gas at about 1300 degrees Fhr. Sufficient gas is introduced to raise the temperature of the resulting mixture to about 975 degrees Fhr. At this point 70 75

the ratio of gas to oil is about 70 cu. ft. of gas per gallon of oil vaporized in column 11. If more than two reaction chambers are employed the same procedure is employed so that the cracking 5 temperature is maintained at about 970 degrees Fhr. at the entrance to each reaction chamber. At the exit of the last chamber the temperature of the mixture is about 940 degrees Fhr. The temperature is reduced during the passage through 10 the stripping column to 450 degrees Fhr. and through the fractionating towers so that at the exit of the last fractionating tower the temperature is about 200 degrees Fhr. The ratio of gas to oil is calculated at atmospheric temperature 15 and pressure.

The effect of time on ultimate yield is substantially as shown:

Time	Percent of original gas oil stock cracked to 437 degrees E. P. gasoline	
	At 975 degrees Fhr. ¹	At 923 degrees Fhr.
16 seconds.....	6.0	4.25
32 seconds.....	8.0	5.25
60 seconds.....	10.25	6.50
120 seconds.....	15.75	9.00
240 seconds.....	21.25	13.0
480 seconds.....	28.50	18.75
960 seconds.....	39.0	26.0

¹ Temperature at start of cracking reaction only and is not the uniform temperature during entire cracking reaction.

35 With a cubical capacity of 30,000 cu. ft. for each of the reaction chambers, two would result in a total capacity of 60,000 cu. ft. If three be used a total capacity of 90,000 cu. ft. will result. If the compressor capacity is such that the gas is circulated at the rate of 15,000 cu. ft. per minute, the cracking time for two chambers would be 4 minutes and for three chambers would be 6 minutes. By bringing the cracking temperature up to 975 degrees Fhr. at the entrance of each chamber, the total conversion would be approximately 45 15.75% for each chamber or 31.50% for two chambers or 47.25% for three chambers, etc. If fresh hot gas be not added at the entrance of each chamber the total conversion would be 15.75% @ 50 975 degrees Fhr. in the first chamber, 9.0% @ 925 degrees Fhr. in the second chamber, and approxi-

mately 3% @ 875 ° F. in the third chamber etc., or a total of 24.75% for two chambers and 27.7% for three chambers etc.

If the volume of gas circulated be 75 cu. ft./gal. of oil, at atmospheric pressure the capacity of the 5 system would be approximately

$$\frac{30,000}{75 \times 2} = 200$$

gallons per minute. If the system pressure be 10 105# absolute, the capacity of the same unit would be

$$\frac{30,000 \times 7}{75 \times 2} = 1,400$$

15 gallons/minute. Since the oil is vaporized before entering the cracking zone, the only effect of pressure is to increase the charging capacity of a unit of fixed cubical volume.

What I claim is:

1. In a process in which a hydrocarbon oil is heated to vaporizing temperatures and separated into vapors and unvaporized oil and the vapors admixed with hot gases in successive steps and time intervals of reaction are permitted after each successive admixture of hot gases, the improvement which comprises admixing the hot gases with the oil vapors in a mixing zone in such quantity and amount as to raise the oil vapors to active vapor phase cracking temperature, and supplying the time interval of reaction by reducing the velocity of flow of the mixture, and permitting the cracking to take place substantially solely by the sensible heat of the hot carrier gas. 20 25 30

2. In a process in which a hydrocarbon oil is heated to vaporizing temperatures and separated into vapors and unvaporized oil and the vapors admixed with hot hydrocarbon gases in successive steps and time intervals of reaction are permitted after each successive admixture of hot hydrocarbon gases, the improvement which comprises admixing the hot hydrocarbon gases with the oil vapors in a mixing zone in such quantity and amount as to raise the oil vapors to active vapor phase cracking temperature, and supplying the time interval of reaction by reducing the velocity of flow of the mixture, and permitting the cracking to take place substantially solely by the sensible heat of the hot hydrocarbon carrier gas. 35 40 45 50
